UNITED STATES PATENT OFFICE

WILLIAM H. OSMER, OF ST. LOUIS, MISSOURI.

HORSE-COLLAR PAD.

SPECIFICATION forming part of Letters Patent No. 335,382, dated February 2, 1886.

Application filed August 4, 1885. Serial No. 173,558. (No model.)

To all whom it may concern:

Be it known that I, WILLIAM H. OSMER, a citizen of the United States, residing at St. Louis, in the State of Missouri, have invented 5 certain new and useful Improvements in Horse-Collar Pads, of which the following is a specification.

My invention relates to improvements in hooks for adjustably attaching pads to horse-collars; and my object is to produce a clasp-hook for this purpose which will afford a constant and positive grip upon the rim of a horse-collar without straining or weakening the clasping parts of the hook. I attain this object by the mechanism illustrated in the accompanying drawings, in which—

Figure 1 is a perspective view of my improved hook. Fig. 2 is a central longitudinal section of same. Fig. 3 is an elevation of 20 hook, open and secured to a collar-pad. Fig. 4 is an elevation showing hook as secured to a collar-pad, and the whole attached to a horse-collar.

Similar letters refer to similar parts throughout the several views.

A represents the shank or fixed part of my improved hook, having ears B.

C represents the curved clamping-arm of the hook, provided with ears D.

30 The parts A and C are hinged or pivotally united by passing a pin, E, through the ears B and D. The pin E is encircled by the compressing-spring F, having the ends G and H H, which bear upon the parts C and A, thus 35 retaining the hook in its normal position, as shown in Fig. 1.

I represents the detent or stop in the joint of my improved hook. The hook is secured to the collar-pad L in this instance by the 40 rivets K passing through the pad L and holes J J in the shank A, and riveting the same together, although any other suitable means for securing the hook to the collar-pad may be provided without departing from the spirit of 45 my invention.

M represents a horse-collar. N is the front roll of same.

The parts A and C of this hook may be steel, brass, malleable cast or wrought iron, or any 50 other suitable metal.

The object in making this hook jointed or in two parts, as shown, is that where the part

which encircles the front roll of the horse-collar is in one continuous piece of metal, the constant strain from continued use at that part 55 of the hook soon destroys and renders the hook useless. Especially is this true where these hooks or clasps are constructed of flat steel strips, for to a skilled metal-worker it is obvious that it is extremely difficult to attain 60 as exact a temper in thin steel strips as is required in hooks encircling the small roll of a horse-collar for the purpose designed. Again, when finished in proper temper, the constant expanding strain upon the clasp or hook when 65 in use soon causes it to relax its grip upon the roll of a horse-collar and slip off the same, while by hard-tempering (which is often unavoidable) the hook becomes so brittle that slight expansion breaks it.

The steel-wire hook, having a coil compression-spring, unless carefully attached and removed, has a tendency to cut or gouge the roll of a collar and partially destroy it.

I am aware that there are collar-pad hooks 75 in two parts; but I do not know of any such hook being jointed in the circle of the clasp for the purpose of attaining the beneficial result referred to above. A sliding or extension hook or clasp is objectionable, as it is not positive in its action, the extension -strip being liable to slip back at any time and detach the pad from the horse-collar.

It is to be understood that I am not to limit myself to any precise form or size of the spring 85 F, or manner of applying it, so long as its office is substantially the same in combination with a joint hook, as shown in Fig. 1. One hook is generally attached to each end of the collar-pad L. The whole is then attached to 90 a horse-collar, M, by hooking the clasp over the front roll, N, as shown in Fig. 4.

It will be seen that my improved hook will admit of adjustment on various sizes of horse-collar rolls. The parts A and C being actuated by the spring F, a positive and constant grip upon the collar-roll is attained without straining the parts A and C.

The attachment of hooks to horse-collar pads is not new. I do not claim such a device, 100 broadly; but

What I do claim is—

1. As an attachment to a horse-collar pad, a jointed metal hook consisting of a curved

shank, A, adapted to be secured to a collar-pad, and a clamping-arm, C, pivotally united by a pin, E, and actuated by a spring, F, all substantially as and for the purpose specified.

5 2. A jointed hook for horse-collar pads, having a curved shank, A, adapted to be secured to a collar-pad, and a clamping-arm, C, in combination with a separate independent compression-spring adapted to compress said jointed parts, substantially as and for the purpose described.

10 3. In a hook for horse-collar pads, the jointed part A, adapted to be secured to a collar-pad and provided with ears B, and the clamping-arm C, having ears D, in combination with

15 a pivot, E, and compression-spring F, all substantially as and for the purpose specified.

4. In combination with a horse-collar and collar-pad, a metallic hook consisting of the part A, adapted to be secured to a collar-pad, 20 and the clamping-arm C, jointed in the circle of the clasp, and provided with the pin E, spring F, and detent I, all substantially as and for the purpose set forth.

In testimony that I claim the foregoing I 25 have hereunto set my hand.

WM. H. OSMER.
